DEVICE FOR ASSEMBLING LETTER SHEETS
AND THE LIKE

Clifford A. McKune, San Francisco, Calif.

Application May 6, 1947, Serial No. 746,260

1 Claim. (Cl. 270—58)

1

This invention relates to an improved machine for assembling form letters and the like and has for the primary object to provide an especially constructed device for automatically sorting and dispensing a plurality of typed, multigraphed, mimeographed or otherwise printed sheets of material having different wording and to dispense the said sheets in succession, whereby a complete set of different worded forms are sorted and dispensed in each operation of the machine.

Another object of the present invention is to provide a series of separate compartments for individually retaining each set of forms and to provide means for simultaneously dispensing one form from each compartment into a common receiver each time a lever or the like is manipulated to operate the machine.

A further object of the present invention is to construct the device in the shape of an open box-like structure having a series of separate form containing compartments and to provide a sliding frame over the top of the said structure, which frame carries a series of hingedly secured cross arms having friction grippers positioned thereon in such a manner relative to the partitions forming the compartments that the first positioned form in each compartment is contacted by the grippers and simultaneously dispensed into a common receiver at the bottom of the structure each time longitudinal forward movement is imparted to the said frame.

A still further object of the present invention is the provision of a hingedly secured guide and sheet holding member in each compartment which members are operated in conjunction with the said gripper arms for controlling the individual dispensing of the forms.

A still further object of the present invention is to provide a typed sheet dispensing and assembling device of the character described that is durable, simple in construction, positive in operation, economical to manufacture, and highly efficient and serviceable in use.

Other objects and advantages will be apparent during the course of the following description.

In the accompanying drawings forming a part of this specification wherein for the purpose of illustration like numerals are employed, for designating like parts throughout the same,

Fig. 1 is a side elevational view of the device, showing the levers and operating mechanisms in their normal positions.

Fig. 2 is a side elevational view similar to Fig. 1, with the exception of illustrating the various levers and mechanisms in their operated positions.

2

Fig. 3 is a vertical sectional fragmentary view taken on line 3—3 of Fig. 1, looking in direction of the arrows and particularly illustrates the levers at the front portion of the structure, for the purpose of clarity, the levers in the rear not being shown.

Fig. 4 is an enlarged vertical end sectional view of one of the friction grippers employed in the invention,

10 Fig. 5 is an end elevational view illustrating a means for preventing the grippers from having frictional contact against partitions of certain compartments when the same are not being used.

Fig. 6 is a sectional plan view taken on line 6—6

15 of Fig. 1, looking in direction of the arrows.

Fig. 7 is a front elevational view of the upper portion one of the partitions dividing the structure into a series of compartments,

Fig. 8 is a vertical sectional view taken on line

20 8—8 of Fig. 1, looking in direction of the arrows,

Fig. 9 is a side elevational view of the device, showing the opposite side from that shown in Fig. 1, and

Fig. 10 is an elevational view of the front end

25 of the device.

Referring in detail to the drawings and to the numerals thereof, the numeral 12 designates, as a whole, the supporting structure, preferably in the form of a housing having a bottom 13, opposite side walls 14 and 15 and a front and back wall 16 and 17, respectively. The said side walls of the housing preferably extend upwardly at an angle as illustrated at 18 in Figs. 1, 2 and 9 and the upper extremities thereof are grooved as shown at 19 and 20 in Fig. 10 providing an upwardly slanting track for accommodating a sliding frame 21 that is mounted thereon. Suitable elongated metal strips 22 and 23 are secured to the side walls 14 and 15, at the upper portions

30 thereof for reinforcing the said sides, and also, to properly guide the said sliding frame 21. The housing is provided with a plurality of spaced partitions 24, which partitions transversely extend across the inside of the housing and are secured to the side walls 14 and 15 thereof and

35 vertically slant upwardly through the sliding frame 21 as shown to advantage in Figs. 1, 2 and 6. Each of the said partitions are provided with a shelf 25 as shown in Fig. 8 for carrying a suitable quantity of typed sheets of material. Thus a plurality of upper compartments, A, B, C, D, E and F are provided and arranged in series for retaining sheets having different wording.

40 From the foregoing description taken in conjunction with the accompanying drawing it will

be obvious that a complete set of typed sheets can be assembled in the different upper compartments, the compartment A carrying the first series sheets, B the second series of sheets, C the third series of sheets, etc. Each of the said partitions 24 are bent at an angle below the shelf 25 forming guides 26 which extend downwardly to the front end portion of the housing, whereby a series of narrow receiving compartments G, H, I, J, K and L are provided in the lower front portion of the housing and into which the sheets are individually dispensed.

The means provided for individually dispensing the said sheets is shown as comprising a plurality of transversely extending arms 27, which arms are provided with friction grippers 28 and are arranged in series and pivotably secured to the sliding frame 21 as at 29, shown to advantage in Figs. 1, 2 and 6. It will be particularly observed that an arm 27 extends through each compartment, whereby the grippers on each arm contact the sheets of material in each compartment. In addition to the provision of the gripper arms for dispensing the sheets, each shelf 25, carrying the sheets, is provided with an upwardly extending hingedly secured baffle member 30 for controlling the movement of the sheets.

The said arms and hinged baffle members are operated through the medium of a plurality of levers imparting longitudinal movement to the said sliding frame 21 and oscillating movement to the said baffles 30. The numeral 31 designates a lever pivotally secured to the sliding frame 21 as at 32 and also pivotally secured to the upper crank arm 33 as at 34, shown to advantage in Fig. 1, the said crank arm 33 being keyed to a shaft 35 that extends across the housing and is journaled in the side walls 14 and 15 as illustrated in Fig. 6. A second lever 36 similar to the lever 31 is pivotally secured to the sliding frame 21 and a second upper crank arm 37 similar to the crank arm 33 is secured to the said shaft 35 as shown to advantage in Fig. 9. The lower crank arm 38 is integral with the said upper crank arm 33 and is pivotally connected to the downwardly extending lever 39, as at 40, which lever 39 is pivotally connected to the master lever 41, as at 42, the said master lever 41 being pivotally connected at the outer extremity thereof to the side wall 14 of the housing, as at 43, and is provided with a suitable handle 44 on the inner end portion thereof as disclosed to advantage in Fig. 1. A suitable coil spring 45 is secured to the bottom 13 of the housing and also to an angular arm 46 that is fixed to the said shaft 35, whereby the said master lever 41 is resiliently retained in its upper normal position. It will thus be seen that when the said master lever 41 is moved from its upper normal position to its lower position the sliding frame 21 will be caused to move forwardly to the positions illustrated in Fig. 2, which forward movement will cause the friction grippers 28, carried on the pivoted lever arms 27, to automatically push the first sheet upwardly, of each set of sheets positioned in the various compartments, whereby the said first sheets in the various compartments are moved to their positions to be dispensed in the lower receiving compartments.

The said sheets are designated by the numeral 47 and illustrated in dot and dash lines. The hinged baffle members 30, one of which is positioned on each shelf 25 of the various partitions, are open as shown in Fig. 1 to permit the sheets to

be free during the upward movement thereof and automatically close as shown in Fig. 2 when the sheets have reached their dispensing positions, to positively guide the sheets to the receiving compartments. Each baffle member 30 is preferably formed angular having a flat bottom portion 48 which is hingedly secured at the front end thereof to its respective partition shelf 25 as at 49 in Fig. 8 and is fixed to a suitable small shaft 50 as shown to advantage in Fig. 7. A plurality of small openings 51 are provided in the side wall 14 of the housing for accommodating the said shafts 50 that extend therethrough. A plurality of levers 52 are provided and the upper ends thereof are pivotally secured to the housing wall 14 as at 53 and the lower ends pivotally secured to a common bar 54 as at 55, the said levers 52 being positioned adjacent the outer surface of the housing wall 14 and in proximity the said shafts 50 as shown to advantage in Fig. 1. The front end lever 56 is fixed to the first lever 52 and is pivotally secured to the vertical lever 57 as at 58. The vertical lever 57 is pivotally secured to a second vertical lever 59 as at 60, which second shaft is bent outwardly forming a shoulder 61 that is adapted to be contacted by the master lever 41 when the said master lever is pulled upwardly. The lower portion of the said lever 59 is flared outwardly forming a shoulder 62 that is adapted to be contacted by the pin 63 provided in the said master lever. The numeral 64 designates a suitable plate secured to the side wall 14 of the housing, numerals 65 and 66 designate horizontally extending pins fixed into the said plate and the numerals 67 and 68 designate suitable slots for receiving the said pins whereby the lower vertical lever 59 is properly guided.

In Fig. 1 there is disclosed to advantage the normal positions of the levers, frictional sheet grippers and the hinged baffle members, which baffle members are in their open positions and free from the sheets in the various compartments due to levers 52 retaining the baffle shafts 50 in their upper positions. When the master lever 41 is moved downwardly to move the first sheet in each compartment upwardly as hereinbefore explained, the pin 63 will abut the shoulder 62 on lower vertical lever 59, at time when the said first sheets are in a position to be dispensed, and the downward movement of the said pin 63 against the shoulder 62 of the lower vertical lever 59 will pull the bar 54 and levers 52 to their downward positions as shown in Fig. 2 which will cause the said baffle shafts 50 to move to their lower positions and close the said baffle members as illustrated in Fig. 2 and shown in dotted lines in Fig. 8, whereby the sheets to be dispensed are prevented from going back in their original compartments and are positively guided to the receiving compartments in the lower front portion of the housing and to the opening 69 completely sorted and assembled. The assembled sets can thus be quickly obtained by pressing the master lever down with one hand and withdrawing the sets with the other.

The numeral 70 designates a guide for the master lever and the numeral 71 a stop pin for the levers 52. The top of the partitions 17 are preferably bent over as indicated at 72. A clip 73 may be placed on the top of the said partitions as shown in Fig. 5 to prevent the grippers from rubbing the partitions when all of the compartments are not in use. The grippers 28 are preferably made of a soft rough rubber or leather and are mounted in suitable retainers 74, which retainers are welded or otherwise substantially secured to the arms 27,

The said arms are formed with oppositely disposed parallel lever like end portions 75, whereby an oscillating movement is obtained. The front portion of the partitions at the housing opening 69 are cut out as shown in dotted lines at 76 in Fig. 10 to provide a hand hold for receiving the dispensed sheets.

It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described my invention,, I claim:

A device of the character described for assembling letter sheets and the like comprising a top open ended housing, a series of upwardly extending partitions spaced in parallelism across the upper portion of the housing and rigidly secured to the side walls thereof, a plurality of shelves, one of which is fixed to each of the said partitions and capable of supporting a plurality of letter sheets upwardly between each of the partitions, an upwardly extending hinged member on each shelf for retaining the letter sheets thereon, an open frame slidably supported on the top of the housing, a lever control mechanism for operating the frame, means on the frame capable of raising and individually dispensing the sheets from the
